UNITED STATES PATENT OFFICE.

LEWIS LOMANDO, OF HAZLETON, PENNSYLVANIA.

CHAIN CONVEYER.

Application filed July 15, 1926. Serial No. 122,551.

My invention relates to chain conveyers and more particularly to means for attaching the carrier to the chain.

Difficulty has been experienced in disconnecting the links of a conveyer chain at the point where a carrier was connected to the chain. This was due to the bulky construction of the attachment which was in the way of disconnecting the links. This attachment was first removed and then the links disconnected. Removing the attachment was a difficult job owing to the worn and corroded securing bolts which were usually broken or cut off by the workman removing the attachment.

A further objection to the old attachment is that it frequently became loose and not being detected, soon became worn beyond further use.

The objects of my invention are to provide carrier attaching means for conveyer chains which, when applied to a chain link, will allow the links to be readily disconnected and will be free of liability of becoming loose on the link, thus lengthening the life of the conveyer and avoiding costly delays due to break-downs and repairs.

These objects, and other advantageous ends which will be described hereinafter, I attain in the following manner, reference being had to the accompanying drawings in which

Figure 1 is a fragmentary plan view of a conveyer chain employing my carrier attaching means,

Figure 2 a side elevation of the chain shown in Figure 1,

Figure 3 a section on line 3-3 of Figure 2,

Figure 4 a section on line 4-4 of Figure 2,

Figure 5 a side elevation similar to Figure 2 with the carrier attaching members removed from the link,

Figure 6 an inner face view of an attaching member,

Figure 7 a fragmentary plan of a conveyer chain provided with a modified form of my carrier attaching means,

Figure 8 a side elevation of the chain shown in Figure 7, and

Figure 9 a section on line 9-9 of Figure 8.

Referring to the drawings, 1 indicates a chain which is of the type requiring shifting of the links toward each other to effect

a disconnection of the outer links 2 from the inner link 3, which are connected by a pin 4 passing through slots 5 in the ends of the links. Each slot has its inner end 6 enlarged and a semi-circular bearing 7 in its outer end. Journals 8 on pin 4 fit in bearings 7 and heads 9 on the ends of the pin, being of greater diameter than the width of the slot, prevent endwise shifting of the pin out of the links, and being of less diameter than the enlarged ends 6 of the slots, may be readily slipped out of the links through the aligned enlarged ends, after the links have been shifted toward each other to bring the enlarged ends into alignment.

My carrier attaching means is connected to the inner link 3 and is of such construction as will allow free shifting of the link to effect a disconnection. Said means include a recess 10 on each side of the inner link and tenons projecting from the link in each recess. One pair of tenons 11 is located in a horizontal plane in each recess and another pair of tenons 12 is located in a vertical plane in each recess. A carrier attaching member 13 fits in the recess and has mortises fitting the tenons. One pair of mortises 14 snugly fit the horizontal faces 15 of tenons 11 and another pair of mortises 16 snugly fit the vertical faces 17 of tenons 12. Fitting the mortises on the tenons in this manner avoids accurate workmanship in positioning the mortises and tenons and yet enables a snug fit of the mortises and tenons to rigidly hold the carrier attaching member to the link. The side extensions 18 of the carrier attaching member

are of such thickness that, when in the recess, their outer sides 19 are substantially flush with the outer sides 20 of the inner links as shown in Figure 1. This allows the outer links 2 to be shifted toward the inner link 3 past extensions 18 and tenons 12 when disconnecting the links. Each member 14 is secured in the recess preferably by bolts 21 passing through the link, and has an upwardly projecting lug 22 to which a carrier, such as a flight 23, is secured. Other means may be substituted for the lug which best suit for securing the type of carrier used with the chain.

In the form shown in Figures 8 and 9, an inner link 25 has a mortise 26 on each side in which tenons 27 of carrier attaching members 28 fit. A carrier 29, such as a flight, is secured to the members 28 prefer-

ably by bolts. The means for connecting the links differ from the means shown in Figures 1-6 in construction only; the manner of disconnecting the links being the same, 5 that is, the outer links 30 are shifted toward the inner link 25. Instead of making the pin as shown in Figures 1-6 free of the links, the pin 31 is made integral with the inner link 25 and has journal parts 32 fitting 10 slots 33 similar to slots 5. The outer links may be shifted toward the inner link for disconnecting the links without interference from the carrier attaching members 28, the outer sides of tenons 27 being substantially 15 flush with the sides of the link.

In a conveyer chain employing the carrier attaching means above set forth, the links may be readily disconnected because the carrier attaching members 14 have their extensions 20 flush with the sides of the inner link. This allows the outer links to be shifted toward the inner link to effect a disconnection. The carrier attaching members 14 are rigidly connected with the link due 25 to the mortised connection therewith and in use are practically free of the possibility of becoming loose, thus lengthening the life of the conveyer and avoiding shut-downs for 30 repairs.

While I have described my invention as taking a particular form, it will be understood that the various parts may be changed without departing from the spirit thereof, and hence I do not limit myself to the precise 35 construction set forth, but consider that I am at liberty to make such changes and alterations as fairly come within the scope of the appended claims.

Having thus described my invention, what 40 I claim as new and desire to secure by Letters Patent is:—

1. In a chain conveyer, a link; a pair of opposed carrier attaching members mortised to the opposite sides of the link, said members being substantially flush with the outer sides of the link, and a carrier secured to the members.

2. In a chain conveyer, a link; tenons on the opposite sides of the link; a carrier attaching member secured to each side of the link and having mortises fitting the tenons in flush juxtaposition with each other, and a carrier secured to the members.

3. In a chain conveyer, a link; tenons pro-

jecting from the opposite sides of the link; 55 a carrier attaching member secured to each side of the link and having mortises fitting the tenons; a lug on each member, and a carrier secured to the lugs.

4. In a chain conveyer, a link; tenons projecting from the opposite sides of the link; 60 a carrier attaching member secured to each side of the link and having mortises fitting the tenons, one mortise snugly fitting only the horizontal faces on one tenon and another mortise fitting only the vertical faces 65 on another tenon, and a carrier secured to the members.

5. In a chain conveyer, a link having a recess between its ends at each side; tenons 70 projecting from the link in the recess; a carrier attaching member secured in each recess and having mortises fitting the tenons, and a carrier secured to the members.

6. In a chain conveyer, a link having a 75 recess between its ends at each side; a carrier attaching member mortised in each recess, the sides of said carrier attaching members being substantially flush with the outer 80 sides of the link, and a carrier secured to the members.

7. In a chain conveyer, a link having a recess between its ends at each side; tenons 85 projecting from the link in each recess; a carrier attaching member secured in each recess; extensions on the opposite sides of each member having mortises fitting the tenons and disposed in the recess with the outer sides substantially flush with the sides of the link, and a carrier secured to the 90 members.

8. In a chain conveyer, a link having a recess between its ends at each side; a pair of tenons projecting from the link in each recess and disposed in a horizontal plane; 95 a second pair of tenons projecting from the link in each recess and disposed in a vertical plane; a carrier attaching member secured to the link in each recess and having mortises fitting the tenons, one pair of mortises snugly fitting the horizontal faces of the first mentioned tenons and the other pair of mortises snugly fitting the vertical faces of the last mentioned tenons, and a carrier secured to the members.

In testimony whereof I have signed my name to this specification.

LEWIS LOMANDO.
